FRANK R. BOLZ, OF SOMERVILLE, MASSACHUSETTS.

WARDROBE-TRUNK.

1,076,479.

Specification of Letters Patent.

Patented Oct. 21, 1913.

Application filed May 17, 1913. Serial No. 768,242.

To all whom it may concern:

Be it known that I, FRANK R. BOLZ, residing at Somerville, in the county of Middlesex and State of Massachusetts, have invented certain Improvements in Wardrobe-Trunks, of which the following is a specification.

The present invention relates to improvements in travelers' trunks and has especial reference to the type denominated as wardrobe trunks in which articles of clothing such as men's and women's suits can be placed upon hangers and suspended within the body of the trunk.

15 In such trunks as commonly arranged the suspended clothing lies flat somewhat in layers each of which have to be lifted away from the others, or the trunk has to be stood upon end while the outer cover or lid is thrown back to reach the garments.

20 My improvement consists of hinging a tray inside the trunk body in such a fashion that after the lid of the trunk is raised it may be elevated on end and swung outside the body into a vertical position and there held rigidly while the lid may be closed if desired. While in this elevated position outside the body of the trunk suits of clothing may be hung inside the tray and a follower 25 pressed upon them to hold them firmly in place, and then the tray turned down inside the trunk. And to remove clothing the reverse movements are carried out, as when the tray is elevated to the fixed rigid vertical position outside the trunk any article 30 can be easily and conveniently removed without disturbing the remainder.

35 My improvement is adaptable to any style of trunk of ordinary make and may be applied thereto without mutilating the same, as no specially constructed body is requisite.

40 In the drawings which accompany this specification and illustrate the same, Figure 1 is a side view of a trunk showing its tray 45 elevated on end on the outside of its body; Fig. 2 is an end view of the same; Fig. 3 is a sectional view of the trunk enlarged; Fig. 4 is a partial plan view of Fig. 3; Fig. 5 is a sectional view of the trunk; Fig. 6 is 50 a side view of the bracket detached.

55 In the drawings A represents the trunk as a whole, while a and b are the bottom and lid thereof, and c is a movable tray supported on cleats inside the trunk in the usual way. The hinges h h upon which the tray turns are bent at right angles near the

center of their length and one part extends through one end of the trunk and is fastened thereto on the outside by bolts, while the opposite part or end is fastened by bolts 60 to the bottom of the tray, and are so proportioned that when the free end of the tray is elevated it will swing outside and away from the trunk as shown in the figures. The iron bracket d on which rests the tray 65 when it is swung out of the trunk has one end d² to serve as a pintle upon which is a projecting stud d⁷, and has an extension d³ to the right terminating in the inward projecting hook d⁵. Normally the bracket is 70 turned inward across the trunk as shown in Fig. 4, its extension d³ lying in the space between the end c² of the tray and the end wall a² of the trunk, the pintle d² playing in the lug f which is riveted to the said wall. 75

Normally the tray lies inside the trunk, and when it is desired to use the same or to get at articles below it in the trunk, the bracket is raised and swung outward and lowered to the edge of the end wall a² of 80 the trunk which enters and rests in the gap d⁴ in the bracket, and the stud d⁷ rests in a slot f² in the upper edge of the lug f, and the end of the brace d⁶ bears on the pin a⁴ in the end of the trunk. It will be seen that 85 when in this position the bracket is rigidly held to the trunk, and adapted to bear the weight of the tray when its inner or free end is raised and it is swung outward on its hinges h h into the vertical position represented by the figures until the bolt of the spring catch k snaps under the end of the hook extension d⁸, whereupon the tray is held from falling backward and its end bears upon the upper face of the bracket. 90

When the tray is elevated and supported on the bracket, the lid b may be lowered and raised at will, and the articles in the trunk reached; and when thus elevated the follower or frame c⁸ which bears upon the 100 clothing in the tray may be taken out and the suits or clothes upon the supports c⁷ which hang on the extension rod c⁸ (not fully represented) may be removed or others put in place, after which the follower is replaced and the tray may be lowered into the trunk. To return the tray to the inside of the trunk, the catch k is released and the tray laid down onto its cleats turning inward on its hinges h h, then the bracket is 105 raised to release the pintle stud from its slot, and permit the extension d³ and brace 110

*d*⁶ to be turned inward so that the bracket may be pressed down into the space between the tray and the end of the trunk.

It will be understood that the precise structure described may be changed without departing from the spirit of the invention.

Placed around the trunk at the meeting line of the lower part *a* and the lid *b* is a valance *v* which consists of a band or strip of iron secured to the edge of the lid and so disposed that its lower part covers the meeting line, shown in Figs. 3 and 5, and the bracket *d* and the hinges *h h* are adapted to pass through the end of the trunk below the valance without cutting or mutilating the latter; so that whether the lid is lowered or raised the tray can stand outside the trunk.

20 I claim as my invention:

1. In a trunk provided with a removable tray with a space between one end and the end of the trunk, means consisting of a bracket located in said space adapted to be extended beyond the end of the trunk, one or more hinges attached to the tray and to the body of the trunk, whereby the tray may be elevated and swung outside the trunk upon said bracket.

30 2. In a trunk having a removable tray with a space between one end and the end of the trunk, means consisting of a bracket located in said space secured to the inner end of the trunk and adapted to be extended beyond and outside said end, one or more hinges attached to the tray and the trunk body, whereby the tray may be elevated on one end and swung outside the trunk upon said bracket.

40 3. In a wardrobe trunk, a swinging bracket attached to the inner face of one end of the trunk body normally extending crosswise therewith but adapted to swing outwardly, one or more hinges attached to the tray and to the said end of the trunk body, whereby the tray may be elevated on one end and swung outside the trunk body upon the said bracket.

45 4. In a wardrobe trunk, a swinging

bracket pivoted to a lug on the inner face 50 of one end of the trunk body normally extending crosswise therewith but adapted to swing outwardly and be locked in position, a tray within the trunk, one or more hinges attached by one end to the tray and by the 55 other end to the end of the trunk by means of which the tray when elevated may be swung outside the trunk body and supported upon said bracket.

5. A wardrobe trunk having a tray with 60 a space between one end and the end of the trunk adapted to be elevated endwise and swung outside the trunk at one end thereof, a swinging bracket located in said space and attached to the trunk, and two or more 65 hinges connecting the tray with the outside of the trunk, as and for the purpose set forth.

6. In a trunk provided with a band or valance to cover the meeting line of the lid 70 and body, a tray, one or more hinges attached to the tray and extending through the trunk below the band or valance, and secured to said body.

7. In a trunk provided with a band or 75 valance to cover the meeting line of the lid and body, a tray, a bracket swiveled to the inner end of the trunk and adapted to be extended beyond and outside said end below said band or valance, as and for the 80 purpose set forth.

8. In a trunk provided with a band or valance to cover the meeting line of the lid and body, a tray, one or more hinges attached to the tray and extending through 85 the trunk below the band or valance, with a bracket swiveled to the inner end of the trunk and adapted to be extended beyond and outside said end below said band or valance, as set forth.

90 In testimony whereof, I have signed my name to this specification in the presence of two subscribing witnesses, this 14th day of May 1913.

FRANK R. BOLZ.
